[57] CLAIM

The ornamental design for a sleeping garment for discouraging supine posture, as shown and described.

DESCRIPTION

FIG. 1 is a rear perspective view of a vest for discouraging supine posture showing my new design in use;

FIG. 2 is a rear elevational view thereof;

FIG. 3 is a right side elevational view thereof;

FIG. 4 is a top plan view thereof;

FIG. 5 is a bottom plan view thereof;

FIG. 6 is a front elevational view thereof;

FIG. 7 is a left side elevational view thereof; and,

FIG. 8 is a rear perspective view of an alternate embodiment of the design shown in FIG. 1.

The broken lines partially showing a human form in FIGS. 1 and 8 are for illustrative purposes only and form no part of the claimed design.

FIG. 1

FIG. 2
